UNITED STATES PATENT OFFICE

2,434,118

RESTRICTOR TUBE FOR REFRIGERATING SYSTEMS

Delbert F. Newman, Schenectady, N. Y., assignor to General Electric Company, a corporation of New York

Application July 18, 1945, Serial No. 605,810

3 Claims. (Cl. 62—127)

1

My invention relates to mechanical refrigerating systems employing fixed restrictors for controlling the flow of refrigerant to the evaporating element, and relates particularly to the prevention of the clogging of such restrictors by the freezing of water therein.

When a restrictor tube or so-called "capillary tube" is employed to control the flow of liquefied refrigerant to the evaporator of a refrigerating machine, it sometimes happens that minute quantities of water in the system freeze in the tube and restrict the normal flow of refrigerant therethrough. It has been found that extended operation of refrigerating machines having hermetically sealed motors may result in the formation or collection of small quantities of water in the refrigerant circuit. When a refrigerant is employed in which the water is not chemically absorbed, the water tends to condense and be frozen in the low temperature portions of the system. When the temperature in the restrictor tube falls below the freezing point of water therein, the water freezes in the restrictor and interferes with the normal operation of the machine, sometimes blocking the tube completely and stopping the flow of refrigerant. Accordingly, it is an object of my invention to provide a refrigerating system employing a restrictor tube as a flow controlling device and including an improved arrangement for preventing the blocking of refrigerant flow by the freezing of water in the tube.

Further objects and advantages of my invention will become apparent as the following description proceeds and the features of novelty which characterize my invention will be pointed out with particularity in the claims annexed to and forming part of this specification.

For a better understanding of my invention, reference may be had to the accompanying drawing in which Fig. 1 is a front elevation view partly in section of the upper portion of a household refrigerator including a refrigerating machine embodying my invention; Fig. 2 is an enlarged view of a portion of the restrictor tube of the refrigerating machine shown in Fig. 1; and Figs. 3 and 4 are views similar to Fig. 2 showing further modifications of my invention.

Referring now to the drawing, the household refrigerator illustrated in Fig. 1 includes a cabinet 1 having a food compartment 2 cooled by a refrigerant evaporating unit or evaporator 3 of the flooded type having refrigerant circulating conduits or louvers formed in its side walls in a manner well known to the art and provided with a

2

liquid and vapor separating header 4 in the upper portion thereof. A refrigerant liquefying unit 5 is mounted in a housing 6 on top of the cabinet 1. The liquefying unit includes a hermetically sealed casing 7 within which are arranged a refrigerant compressor and an electric driving motor. The compressed refrigerant is discharged through a connection 8 and flows to a condenser 9 where it is liquefied by air circulated over the surface of the condenser by a fan (not shown) but driven by a motor 10. The liquefied refrigerant is supplied from the condenser through a restrictor tube 11 and flows through the tube to the evaporator which it enters at a connection 12. Refrigerant vaporized in the evaporator is withdrawn therefrom through a suction line 13 and returned to the motor compressor casing 7. The suction line 13 and the greater portion of the restrictor tube 11 are secured together in heat exchange relationship to provide a transfer of heat from the warm liquid refrigerant to the cold vaporized refrigerant being returned to the compressor. During the operation of the refrigerating machine, liquid refrigerant in the evaporator 3, that is, in the low pressure side of the refrigerating system, is vaporized by the absorption of heat from the contents of the food storage compartment 2, the vaporized refrigerant being returned to the liquefying unit 5 in the high pressure side 30 of the refrigerating system where the heat is removed and discharged to the air circulated over the condenser. The warm liquid refrigerant at high pressure enters the restrictor tube 11 and the pressure is reduced as the refrigerant flows 35 through the tube to the evaporator. This reduction in pressure is such that during the normal operation of the system the refrigerant in the tube reaches a temperature below the freezing point of water within the tube. Should it happen that water is present in the refrigerant, this water may freeze in the tube and tend to restrict the tube and even stop the flow of refrigerant.

Flow restricting tubes, such as the tube 11, are designed to pass the required amount of liquid refrigerant under the temperature and pressure conditions prevailing during the range of ambient temperatures for which the refrigerating system is designed. The internal diameter of the tube and its length are also preferably such that the flow of gaseous refrigerant is relatively restricted, it being desirable to provide sufficient resistance to the flow of gas to enable a refrigerating machine to attain quickly after starting the required pressure difference between the high and low sides thereof. It has been found that restrictor

tubes designed to provide operation in this manner occasionally are plugged by the freezing of moisture within the tube, thereby preventing operation of the refrigerating system until the plug has been removed. During the manufacture of hermetically sealed refrigerating systems, extensive precautions are taken to eliminate moisture and the machines are dried as thoroughly as possible before being sealed. However, after operation under heavy load conditions for a long period of time, water vapor may appear in the system. This water vapor may, for example, be the result of high temperature operation of the electric motor windings which are provided with cotton insulation. Refrigerating machines which develop trouble because of the formation of water vapor may be stopped by freezing of the water in the restrictor tube; however, since the ice melts upon a rise in temperature it may happen that the machine which has been stopped by freezing thereafter runs for a considerable period of time before it is stopped again in a manner to plug the restrictor tube. The operation of the machine therefore becomes undependable and may result in frequent calls for service because of the inability of the machine to maintain the required temperatures in the refrigerator cabinet.

The quantities of water present in refrigerating machines are very small, but are sufficient to freeze and plug the conventional restrictor or capillary tube. I have found that the plugging of restrictor tubes due to the presence of this water may be sufficiently minimized or eliminated by constructing a portion of the restrictor tube toward the outlet end thereof to have an increased cross sectional area. For example, as shown in Fig. 2 the restrictor tube 11 is provided with an enlarged portion 14 on the lower end thereof which extends from the evaporator back to the portion of the tube 11 which is soldered in heat exchange with the suction line 13. In Fig. 2 the major portion of the section 14 has been formed as a coil within the insulating material of the top wall of the cabinet. A portion of the section 14 between the evaporator connection 12 and the coil is secured by clip 15 to the suction line 13 as a support. During the operation of the refrigerating machine shown in the drawing, the restrictor tube 11, including the portion 14, operates in the usual manner to determine the rate of flow of refrigerant from the condenser to the evaporator. The section 14 is made of sufficient length to provide a substantial portion of the pressure drop throughout the tube, and its length and diameter are selected so that, throughout the range of operating conditions of the machine, substantially the entire temperature drop from 32° F. down to the temperature of the evaporator is attained within the section 14. It will be apparent, therefore, that when the refrigerant and any water contained therein reach the freezing point of water within the tube, it is within the larger diameter portion 14 of the tube and the increased area is such that the small amount of water in the system is insufficient to freeze and plug the larger cross sectional area of the section 14. I have found that with a relatively small increase in the diameter of the portion 14 over that of the main portion of the tube 11 there is provided a combined tube which will not be plugged by the freezing of water normally formed during the operation of the refrigerating machine over a period of many years. The provision of this type of tube therefore eliminates the danger of plugging and renders the refrigerating ma-

chine reliable in operation over a long period of time without danger of stoppage.

By way of illustration only and not by way of limitation, I have found, for example, that in a refrigerating machine having a capacity of the order of 700 B. t. u. per hour and normally provided with a restrictor tube having an internal diameter of 31 thousandths of an inch, freezing of the tube may be prevented effectively by the addition of a length of tube having an internal diameter of 41 thousandths of an inch. In one such machine the smaller diameter section of the tube was ten feet long and the larger diameter section two feet long.

In Fig. 3 the restrictor tube 11 is provided with an enlarged portion taking the place of the portion 14 in Fig. 2 and comprising a portion 16 of a slightly larger diameter than the main tube and a portion 17 of slightly larger diameter than the portion 16, and in Fig. 4 the second section of the tube has been constructed with its internal diameter increasing gradually from that of the main section, it being provided with a tapered section 18 corresponding to the section 14 of Fig. 2. The stepped increase in diameter in the modification of Fig. 3 and the gradual increase in diameter of the modification of Fig. 4 both provide increased cross sectional areas of the sections in which the temperature of the refrigerant during normal operation falls below freezing. These constructions act in the same manner as that of Figs. 1 and 2 to insure extended operation of the refrigerating machine without plugging of the restrictor tube.

While I have illustrated my invention in connection with a specific type of compression refrigerating machine, other applications will readily be apparent to those skilled in the art. I do not, therefore, desire my invention to be limited to the particular construction illustrated and described and I intend by the appended claims to cover all modifications within the spirit and scope of my invention.

What I claim as new and desire to secure by Letters Patent of the United States is:

1. In a refrigerating system having high pressure and low pressure sides and including a refrigerant evaporating unit and a refrigerant liquefying unit connected in a closed circuit, said evaporating unit and said liquefying unit being on the low and the high pressure sides respectively of said system, a restrictor tube in said circuit separating said high and said low pressure sides for controlling the flow of refrigerant from said liquefying unit to said evaporating unit, the pressure drop through said tube during normal operation of said system being such that the temperature of refrigerant flowing through said tube falls below the freezing point of water in the tube before being discharged therefrom, said tube including a first section comprising the major portion of the length of said tube and a second section of increased cross sectional area, the relative lengths and cross sectional areas of said sections of said tube being such that substantially the entire temperature drop from 32° F. down throughout the normal range of operation of said system occurs in said second section of said tube.

2. In a refrigerating system having high pressure and low pressure sides and including a refrigerant evaporating unit and a refrigerant liquefying unit connected in a closed circuit, said evaporating unit and said liquefying unit being on the low and the high pressure sides respectively of said system, a restrictor tube in said circuit

separating said high and said low pressure sides for controlling the flow of refrigerant from said liquefying unit to said evaporating unit, the pressure drop through said tube during normal operation of said system being such that the temperature of refrigerant flowing through said tube falls below the freezing point of water in the tube before being discharged therefrom, said tube including a first section comprising the major portion of the length of said tube and a second section having a cross sectional area increasing gradually from that of said first section toward the outlet of said tube, the relative lengths and cross sectional areas of said sections of said tube being such that substantially the entire temperature drop from 32° F. down throughout the normal range of operation of said system occurs in said second section of said tube.

3. In a refrigerating system having high pressure and low pressure sides and including a refrigerant evaporating unit and a refrigerant liquefying unit connected in a closed circuit, said evaporating unit and said liquefying unit being on the low and the high pressure sides respectively of said system, a restrictor tube in said circuit separating said high and said low pressure sides for controlling the flow of refrigerant from said liquefying unit to said evaporating unit, the pressure drop through said tube during normal operation of said system being such that the tempera-

15

20

30

ture of refrigerant flowing through said tube falls below the freezing point of water in the tube before being discharged therefrom, said tube including a first section comprising the major portion of the length of said tube and a second section comprising successive lengths of progressively larger cross sectional area beginning at the outlet of said first section and extending toward the outlet of said tube, the relative lengths and cross sectional areas of said sections of said tube being such that substantially the entire temperature drop from 32° F. down throughout the normal range of operation of said system occurs in said second section of said tube.
